The schedule referred to in these Letters Patent and making part of the same.

Be it known, That I, Samuel F. Pratt, of the City of Boston, State of Massachusetts, have produced a new and original ornamental Design for the plates of a Franklin Stove, called by me the Franklin Oval Stove, and I, hereby declare that the annexed drawings are accurate delineations of the said plates (which form the said stove) with the exception of the back plate, not delineated and their ornamental parts, the end plate, not shown in the drawing being symmetrically similar to the plates shown, and the half of the front, top and hearth plates not shown, being also symmetrically similar to the parts shown in the drawings.

What I, claim as my production and desire to secure by Letters Patent is the combination and arrangement of ornamental figures and forms, represented in the accompanying drawings forming together the ornamental design, for the plates of a Franklin Stove.

Signed at Boston, County of Suffolk, State of Massachusetts, this twenty fourth day of July, A. D. 1856.
